UNITED STATES PATENT OFFICE.

GEORGE E. CURTIS, OF PHILADELPHIA, PENNSYLVANIA.

DESIGN FOR A HOLDING-BLOCK FOR BICYCLE-CLIPS.

SPECIFICATION forming part of Design No. 23,160, dated March 27, 1894.

Application filed February 16, 1894. Serial No. 500,423. Term of patent 7 years.

To all whom it may concern:

Be it known that I, GEORGE E. CURTIS, a citizen of the United States, and a resident of the city of Philadelphia, State of Pennsylvania, have invented a certain new and original Design for a Holding-Block for Bicycle-Clips, of which the following is a specification.

The nature of my design is fully illustrated in the accompanying drawing, to which reference is made.

The upper face, A, presents a smooth flat surface within the lines drawn from the points, a, b, c, d; the lines a, b, and c, d, are substantially straight; the lines b, c, and a, d, are drawn to the arc of a large circle curved outwardly, the lines a, e, and b, f, and the corresponding lines on the opposite side of the block, are substantially equal in length, while the lines e, f, and the corresponding line on the opposite side of the block, are equal to, or slightly less than, the length of the lines a, b, and c, d, and have a slight curvature tending inwardly. The central portion of the base of the block, longitudinally considered, is hollow, the lines g, h, and i, j, of the inner side walls being disposed at an acute angle to the upper face of the block, and at oppo-

site angles to each other, the lines h, i, and e, g, and j, k, being horizontally disposed and parallel with the upper face of the block. As 30 illustrated in the drawing the faces of the opposite ends of the block are formed in substantially perpendicular lines respectively, save at or near the upper lines b, c, and a, d, where the upper surface of the block projects over in the arc of a large circle. 35

In my invention, above described, I produce a new and original shape or configuration in holding blocks for bicycle clips presenting in the lines described a design of block conveying 40 the impression of lightness, grace and finish not heretofore produced in such articles.

Having thus described my invention, what I claim, and desire to secure by Letters Patent, is—

The design for a holding block for bicycle clips substantially as herein shown and described

In witness whereof I have hereunto set my hand this 15th day of February, A. D. 1894.
GEORGE E. CURTIS.
